RECORDING APPARATUS

Joseph Walker, Berwyn, Ill.

Application August 9, 1940, Serial No. 351,920

6 Claims. (Cl. 234—70)

The present invention relates in general to recording apparatus, and more in particular to a so-called pen recorder, in which a movable pen is employed to mark a continuously moving tape. The object of the invention is to produce an improved and highly efficient device of this character.

A special object is to provide a pen recorder adapted to make records of two events or series of operations, usually associated with each other, by means of a single pen.

The various features of the invention will be described in detail hereinafter with reference to the accompanying drawings, in which—

Fig. 1 is a side view of the complete pen recorder, with cover in place;

Fig. 2 is an end view, showing the switches, push buttons and terminals;

Fig. 3 is a side view on a larger scale than Fig. 1, and with the cover in section;

Fig. 4 is a top view, also with the cover in section;

Fig. 5 is a side view similar to Fig. 3, but taken from the opposite side;

Fig. 6 is a detail, showing the arrangement for operating the pen;

Figs. 7 and 8 are sectional views of the ink reservoir;

Fig. 9 is a circuit drawing, showing the electrical connections; while

Figs. 10, 11 and 12 show sample records that may be made by the pen recorder.

Referring to the drawings, the cover 1 is preferably an aluminum casting of the shape shown in Figs. 1 and 2. The end wall at the right in Fig. 1 has an opening therein which is closed by the switch panel 2, as shown in Fig. 2.

All the apparatus is mounted on a cast metal frame which comprises the base 3 and two apparatus supporting members which are preferably formed integrally therewith. The first of these members is indicated at 4 and is provided with a rearward extension 5 and a forward extension 6, the latter having a further extension 7 bent at right angles to the extension 6, as shown in Fig. 4. The other supporting member is indicated at 8.

The switch panel 2 is attached to the base 3 by means of a bracket 9, and is also secured to the support extension 7 by means of two spacers 10 and 11. These spacers are secured to the extension 7 at one end by screws 13 and at the other end to the panel by means of screws 12.

On the switch panel there are mounted three push buttons 15, 16 and 17, ten terminals 18 to 28

27, inclusive, and three switches 28, 29 and 30. The push buttons may be of any suitable type. The terminals shown are socket type terminals adapted to receive bayonet type plug terminals attached to connecting cords. Any suitable type of terminal or binding post may be used, however. The switches open and close single circuits and are adapted to remain in either open or closed position.

The paper tape on which the record is made is carried in the form of a roll 31, having a core 32, which is rotatable on the cylindrical member 33. The latter has a reduced portion 34 at one end, which lies in a slot in the vertical extension 35 of member 5, to which it is clamped by means of the knurled nut 36. The roll 31 and core 32 are retained in place by means of the member 37, which has a knurled head 38 and is threaded onto the extension 41 of the member 33. The member 37 is equipped with guide spokes 39 and the member 33 has similar guide spokes 40. It will be seen that an exhausted roll of tape can quickly be replaced by unscrewing the member 37, removing the empty core such as 32, and placing it with a new roll, after which the member 37 can be screwed back on again.

On the vertical supporting member 4, at about the junction of the extensions 5 and 6, there is provided a boss 50, which is drilled through horizontally and forms a bearing for the shaft 51. The shaft is enlarged throughout its central bearing portion, whereby shoulders are formed near each end. At one end of the shaft a feed spool comprising a body portion 58 and end members 56 and 57 is secured, being clamped against the adjacent shoulder on shaft 51 by means of nut 59. The body of the feed spool is covered preferably with a layer of rubber 59, as shown in Fig. 3. The end member 57 is provided with teeth to form a gear wheel.

At the other end of the shaft the gear 52 is secured by means of a set screw 53. A spacer 54 is introduced between the gear wheel 52 and the end of boss 50 in order to prevent any play in the shaft.

The extension support 5 has a shelf 61 formed integrally therewith, on which there is supported the guide 62 for the tape.

Other means for supporting and guiding the tape comprise a spool 46, rotatably mounted on a bracket 45, and spools 43 and 44, rotatably mounted on a bracket 42. These brackets are attached to the extension support 5, as shown. In addition, there is provided an auxiliary feed roller 63, which is mounted on the pivoted brack-

et 64. A spring 65 is provided, which tends to rotate the bracket in such a direction as to cause the roller 63 to press the tape against the rubber surface 59 on the drive spool. The roller 63 is positively driven by a small pinion 66 which is in mesh with the teeth on the end member 57 of the drive spool.

The tape leaves the roll 31 at the rear, as seen best in Fig. 5, passes around spool 44 where it reverses its direction, passes around spool 46 where it again reverses, and after passing over spool 43, arrives at the drive spool 56-57. Here the tape passes around the drive spool, then underneath the roller 63, and finally is received in the guide 62, which directs it to the outlet slot 67 in the cover.

In order to drive the tape feed mechanism, the motor unit 70 is provided, comprising a small synchronous motor adapted to run on commercial power and a set of reducing gears by means of which the shaft 73 is run at the desired speed, preferably 1 R. P. M. The unit is mounted on the support 8 with the pinion 74 in mesh with the gear 52, by means of screws 71 and 72. The pinion 74 is secured to shaft 73 of the motor unit by a set screw 75, and hence is readily detachable, like the gear 52. This makes it possible to quickly substitute a different set of gears in order to drive the tape feed mechanism at a different speed. For instance, if a faster feed is required for some purpose, a larger pinion may be substituted for pinion 74, and a smaller gear for gear 52. The change in gears may require a slight adjustment of shaft 73 in order to make the gears mesh properly, and accordingly the opening in support 8 through which the screw 71 passes is made in the form of a curved slot, as shown in Fig. 5. It will be appreciated that after loosening screws 71 and 72 the motor unit may be rotated about screw 72 as a pivot in order to secure the proper gear adjustment, after which the screws may be tightened up again.

The pen and associated parts, including the operating mechanism for the pen, may now be described. One of the operating magnets is indicated at 80. This magnet is mounted on a heel piece 82, the shape of which will be clear from Fig. 3. The heel piece has an ear 83, bent at right angles to its right hand vertical portion, which is secured to the extension support 6 by means of screw 84. The other operating magnet 81 is mounted on a heel piece 87, which is secured to the heel piece 82 by means of two screws as shown. There are two springs 91 and 92, four flat terminal members 90, and a flat spring 88, which are clamped between the two heel pieces, the four terminal members 90 being suitably insulated by thin strips of insulating material. The winding of the two magnets may be connected to these terminal members. The magnet armatures are indicated at 85 and 86.

The reference numeral 93 indicates the ink reservoir, which is shown on a larger scale in Figs. 7 and 8. The reservoir 93 is made from a length of metal tubing and is closed at its opposite ends by screw threaded plugs 99 and 100. The reservoir is attached to the lower end of bracket 82 by means of a screw 94. The pen comprises a main horizontal section 95, a vertical marking section 96, the end of which rests on the tape, and a vertical feed section 96'. The marking section is of reduced diam-

eter and has a fine bore of capillary size. The feed section 96' fits loosely in the bearing member 97, and its end rests on the bottom of the reservoir 93. The bearing member 97, and also the filler tube 98, pass through the wall of the reservoir as shown, and may be secured in place by soldering. It will be observed that the pen is pivoted in the bearing member 97 for movement in a horizontal plane.

The pen is operated by means of the lever 101, which is shown more clearly in Fig. 6. This lever is pivoted on the heel piece 82 by means of a shoulder screw 102 and is slotted at both ends. At the lower end there is a vertical slot 104 for receiving the horizontal portion 95 of the pen. At the upper end there is a diagonal slot 103 through which there projects a short pin 89 attached to the end of spring 88.

The springs 91 and 92 are equally tensioned toward each other and normally maintain the spring 88 and pin 89 in the position shown. When magnet 80 is energized, its armature 85 presses the spring 88 upward and moves pin 89 upward in the slot 103, thereby rotating lever 101 in a clockwise direction as seen in Fig. 6, and moving the pen 95 to the left. When magnet 81 is energized, its armature 86 presses the spring 88 and pin 89 downward, which rotates the lever 101 in a counter-clockwise direction and moves the pen to the right.

The lever 101 has a side slot 105, communicating with slot 104, and adapted to support the pen with the marking section 96 thereof off the tape. The bearing at 97 is loose enough so that the pen can be readily shifted from one slot to the other.

The interior of the casing, and particularly that portion thereof where the tape is marked, may be illuminated by means of a small lamp 107. The lamp is mounted on a socket 106, having terminals 108 and 109, and secured to the extension support 5-36 by means of a bracket 110. When the lamp is lighted the tape and other parts can be observed through the window 111 in the top of the cover.

The apparatus is preferably furnished with an extra supply of ink contained in the bottle 112, which is held in the clip 113, the latter being suitably attached to the base 3. The reservoir 93 is filled by means of a small syringe 114, which is normally retained in a clip 117. The syringe has the usual rubber bulb 116 at one end and a small section of fine rubber hose 115 at the other. By means of this syringe a supply of ink can be withdrawn from the bottle and then, after attaching the hose to the filler pipe 98, can be discharged into the reservoir 93.

The syringe is also used for starting the flow of ink through the pen. The end of the hose 115 is slipped over the marking end of the pen, which is first raised from the tape, and then suction is applied by means of the syringe. The bulb 116 is preferably compressed before the hose is attached to the pen and is then released gradually until ink appears in the syringe just above the hose. The syringe can then be removed and the pen can be replaced on the tape. After being started in this way the pen will continue to function until the ink in the reservoir is exhausted.

It will be observed that the reservoir construction according to which the bearing tube 97 and the filler tube 98 are sealed in the upper wall of the reservoir and extend substantially to the bottom wall thereof affords a protection against loss

of ink in case the pen recorder is accidentally knocked over. In fact, the recorder can be turned upside down and only a few drops of ink will be lost.

The circuit connections at the switch panel 2 may now be described briefly in connection with Fig. 9, which shows the wiring of the pen recorder.

Terminals 26 and 27 are the alternating current supply terminals and should be connected to a 110-volt supply line in some convenient manner, as by an extension cord. The motor 70 is connected in series with these terminals and the switch 30.

If an outside supply of direct current is available, it may be connected up at terminals 22 and 23 or at terminals 24 and 25. If the voltage is about 6 to 15 volts, the connection is made at terminals 22 and 23, but if the voltage is 110 volts, the connection is made at terminals 24 and 25, thereby including the resistance which is connected between terminals 22 and 24.

The pen recorder is preferably provided with a small 9-volt dry battery, B, for which there is room inside the cover, which is connected across terminals 22 and 23 in series with the switch 29. An outside direct current source should be used if available in order to conserve the dry battery, and at such times the switch 29 is left open.

The positive direct current terminal 23 is connected to terminals 21 and 19, and also to the push buttons 15, 16 and 17. The negative direct current terminal 22 is connected by way of switch 28 to the magnets 80 and 81 and to the lamp 107. Terminal 18, and also push button 16, is associated with magnet 80, while terminal 20 and push button 15 are associated with magnet 81. The push button 17 is for lighting the lamp 107.

The operation of the pen recorder may now be described. For this purpose it may be assumed that 110-volt commercial power is connected across terminals 26 and 27, and that a source of direct current, which may be battery B or an outside source, is connected across terminals 22 and 23. It may be assumed also that switch 28 is closed.

When the switch 30 is closed, current is supplied to the motor unit 70, and the motor starts to run, rotating the shaft 51 by means of pinion 14 and gear 52. Shaft 51 rotates the tape feed spool 56-57 in a counter-clockwise direction, as seen in Fig. 3. The end member 57 of the feed spool drives the roller 63, and the spool and roller cooperate to draw the tape off the roll 31 and feed it along through the guide 62 and out through the slot 67 in the casing or cover 1. The moving tape passes underneath the marking end 96 of the pen, which rests on the tape, and thus a straight median line is drawn on the tape parallel to its edge, as indicated at 120, Fig. 4.

If the push button 16 is operated now and held operated for a moment, a circuit will be closed in an obvious manner for the magnet 80, which energizes and moves the marking end of the pen to the left in the manner previously described. It follows that during the time the magnet is energized the line traced by the pen will be offset to the left, as indicated at 121.

If the push button 15 is now operated for a moment, the magnet 81 will be energized and will move the marking end of the pen to the right, causing the pen to trace a line which is offset to the right, as indicated at 122.

It will be understood that in speaking of right and left offset lines, the assumption is made that

the tape is being observed as it comes out of the slot 67 in the cover. It will be seen that the pen is capable of drawing a line along the tape having any one of three positions, a central position when no magnet is energized, a left hand position when magnet 80 is energized, and a right hand position when magnet 81 is energized.

The operation of the pen recorder as just described, through the medium of the push buttons 15 and 16, is performed merely for testing purposes, but affords a convenient opportunity of explaining the function of magnets 80 and 81 and their control over the pen. While the testing is going on, the operation of the pen and other parts can be observed if desired through the window 111. For this purpose the push button 17 should be operated to close a circuit for lamp 107, which will light up the interior of the casing.

When the pen recorder is used in practice, the pen is controlled over circuits which are connected at terminals 18-19 and 20-21. It may be assumed, for instance, that the pen recorder is to be used for making a record of the production on some type of automatic machine, such as a punch press, for example. In order to connect up the pen recorder, a two-conductor circuit may be employed, connected at terminals 20 and 21, and leading to the machine, where suitable means is provided for connecting the conductors together when the power is turned on at the machine and for momentarily breaking the circuit at each operation of the machine. Such control means is well known and forms no part of the invention, and hence is not shown herein.

It will be clear that with the foregoing arrangement, the magnet 81 will be energized when the power is turned on, moving the pen to the right and starting an offset line, as indicated at 130, Fig. 10. At each operation of the machine the circuit is momentarily broken, magnet 81 momentarily deenergizes, and the pen momentarily restores, thus making a series of marks such as 131. These marks constitute a record of the machine operations, and show the number of parts completed. Short gaps in the steady operation of the machine are indicated at 132 and 133, and a temporary shutdown is indicated at 134. It will be seen that the pen recorder affords means for making a complete record of the production of the machine.

Fig. 11 shows a portion of a record made by the pen recorder in connection with the operation of a concrete mixer. In this case two circuits are used. Circuit No. 1 is connected to terminals 20 and 21 and is closed at the mixer while the actual mixing operation is going on. Circuit No. 2 is connected at terminals 18 and 19 and is closed at the mixer while the same is in loading position. In the unloading position both circuits are open.

With the above described arrangement, magnet 81 is energized during each mixing operation and causes the pen to draw a line offset to the right, as shown at 135. While the mixer is being emptied, both magnets are deenergized and the pen draws a median line, as shown at 136. During the loading operation magnet 80 is energized, and the pen draws a line which is offset to the left, as shown at 137. The record makes it possible to check up on the proper operation of the mixer at the end of the day or at any time that a check is deemed necessary, and improper or unusual operations are at once disclosed upon inspection of the record. For instance, the record at 138 shows a short mixing

period, while at 139 it shows an exceptionally long loading period.

Fig. 12 shows a portion of a record made when the pen recorder is used to supervise the operation of an elevator. Two circuits are used as in the preceding case and control means is employed so arranged that it will close one circuit when the elevator is going up and the other when the elevator is going down. When the elevator is stopped, both circuits are open. The 10 arrangement preferably also provides for momentarily opening the circuit in use when the elevator passes a floor, even though the elevator does not stop.

From the above description of the control arrangement the meaning of the record will be readily understood. Thus the line at 140 indicates that the elevator is standing still, while the line beginning at 141 indicates upward movement of the elevator. The first three marks such as 142 show that the second, third and fourth floors were passed without stopping. The median line at 143 indicates that the elevator made a stop at the fifth floor. Other stops are indicated at 144, 145, and 146. The short median line at 147 indicates the stop at the top floor, the nineteenth. The line starting at 148 corresponds to the descent of the elevator. It will be noticed that the record at 149 shows a long stop at the thirteenth floor.

The pen recorder may be used in numerous other situations, as will be apparent from the examples described.

Single conductor control circuits may, of course, be used if desired. When single conductor circuits are to be used, the terminal 23 is connected to ground, and the conductors of the two control circuits are connected to terminals 18 and 20. The control devices at the machines or other apparatus whose operations are to be recorded are then arranged to ground the control conductors.

The invention having been described, that which is considered new and desired to have protected by Letters Patent of the United States is defined in the appended claims.

What is claimed is:

1. In a recording apparatus, a marking pen, means for moving a mark receiving surface underneath said pen, supporting means for said pen adapting the same to move in a horizontal plane to change the position of the line it draws on said surface, a pair of magnets mounted one above the other, a common element adapter to be moved in either direction in a vertical plane

by said magnets, and translating means for causing the movement of said element to control the movement of said pen.

5 2. In a pen recorder, a base member, an upright switch panel supported at one end of said base, recording apparatus including a mark receiving surface, mechanism for feeding said surface and a marking pen supported on said base, magnets for controlling said pen wired to said panel, and a cover cooperating with said base and panel to enclose said recording apparatus, said cover having an opening at one end which is closed by said panel when the cover is in place.

3. In a pen recorder, a marking pen adapted to draw a line on a moving strip of tape, a vertical lever pivoted between its ends and having its lower end engaging said pen to move the same toward either edge of said tape, said lever having an inclined slot at the upper end, a member movable up and down in said slot to actuate said lever, and two electromagnets for moving said member up and down, respectively.

4. In a pen recorder, a marking pen comprising a horizontal section pivoted at one end for movement in a horizontal plane and a downwardly extending marking section at the other end, two electromagnets arranged one above the other above the horizontal section of said pen and in the vertical plane thereof, a member movable up and down in said vertical plane by said magnets, respectively, and means for communicating movement of said member to said pen comprising a vertical pivoted lever having a slot at one end through which the horizontal section of said pen extends and inclined cam surfaces at the other end engaged by said member.

5. In a pen recorder, a horizontal tubular ink reservoir and two horizontal electromagnets disposed in superimposed relation in a vertical plane, a horizontal marking pen extending parallel to said reservoir and having a vertical pivot section extending into the said reservoir a vertical pivoted lever for moving said pen on its pivot, armatures for said magnets, and means for operating said lever controlled by said armatures.

6. In a pen recorder, a rectangular base, an upright switch panel supported on said base at one end thereof, elements of said pen recorder mounted on said base and wired to the rear of said panel, and a cover cooperating with said base and panel to enclose said elements, said cover having an opening at one end which is closed by said panel when the cover is in place.
